UNITED STATES PATENT OFFICE

MILLARD FERN, OF JUNIATA, PENNSYLVANIA

MANIFOLD ATTACHMENT

Application filed July 20, 1927. Serial No. 207,254.

The present invention relates to humidifiers and particularly to humidifiers to be used in connection with internal combustion engines.

Important objects of the invention are the effective prevention of carbon formation in the cylinders of the engine; the prevention of overheating of the motor; and the effecting of smooth running thereof; the obtaining of more even burning of fuel and consequent economy thereof; and the economy of cooling oil.

A further important object is to effect a richer pick up of moisture by the air passing through the humidifier to the engine manifold.

A further object is to provide for supplying water to the humidifier without dismounting it from the vehicle and by suction applied by the engine.

In the drawings forming part of this specification:

Figure 1 shows a form of my humidifier attached to an automobile and connected with the manifold of an engine.

Figure 2 is a longitudinal section through the humidifier on an enlarged scale compared with Figure 1 and showing the internal construction thereof.

Referring to the drawings in detail, 10 designates a cylindrical receptacle having straight walls and 11 is a cap fitting snugly on the upper end thereof and forming a closure therefor, said cap having a circumferential flange 12 having apertures formed therein

and being held in place by means of rods 13 extending longitudinally of the cylindrical receptacle, and a cup-shaped member 14 fitting over the bottom thereof and provided with apertures, a flange 15 cooperating with the rods, the rods having heads at one end passing through the apertures of the cap and cup-shaped members for drawing them together and securing the cap firmly in place. Depending into the vessel from its upper end are a plurality of cylindrical members 16 and 17 having closed bottom ends 18 and 19, the upper ends of these cylindrical members being secured to a circular plate 20 adapted to be placed on the top of the cylindrical member 10 and to extend over the edges

thereof, said circular plate being held in place between the cap 11 and the upper end of the vessel 10. The members 16 and 17 may be secured to the circular plate in any suitable manner, as by having flanges 21 and 22 formed thereon which may be soldered to the circular plate 20. The members 16 and 17, while shown as two in number, may be multiplied to any suitable number found desirable or convenient in a device of this character. The alternate members in any case should have apertures formed therein alternately at the lower and upper ends of the cylinders, as shown at 23 and 24. Leading from the space around the outer cylinder is an outlet 25 to which a valve controlled pipe 26 is attached, which leads to the manifold 27 of the engine, and arranged centrally of the vessel is a tube 28 depending from the cap to a point near the bottom of the inner cylinder. This pipe is open at its bottom and extends through the disk 20 and the cap 11, to which it may be secured by threaded connection as at 29 with a nipple 30 having a flange resting beneath the plate 20 and a coupling 31 connected with its upper end, the upper end of the coupling being connected with a pipe 32 which is bent upon itself and extends downwardly along the side of the vessel and spaced a suitable distance therefrom. The coupling 31 is in the form of a check valve and has a ball therein as shown for controlling the pipe 32. The ball is normally supported by a pin.

A suitable bracket member may be provided formed of sheet metal and having a strip 33 extending longitudinally of the cylinder 10 and provided with straps 34 surrounding said cylinder and having the ends thereof adjustably connected in any suitable manner, said member 32 being bent at its lower end to extend under the vessel as at 35.

It will appear from the above disclosure that I have provided a device, simple in construction, which may be attached to the manifold of an automobile and which when partially filled with water will form a means for humidifying the air fed to the manifold.

The operation of the device is as follows: When the vessel 10 is connected with the manifold of the engine, the lower end of

the tube 32 being open, air will be drawn therethrough, passing downward through the tube 28 and upward through the water within the cylinder 17. The air will pass 5 through the apertures 24 at the top of this cylinder and again down through the water contained between the walls of the cylinders 16 and 17, passing out through the apertures 23 in the bottom of the cylinder 16, then upwardly through the water and out through the outlet 25 to the manifold. Air passing through a circuitous passage of this sort will be thoroughly humidified and will have taken up a maximum amount of moisture. 10 The greater number of times the air passes downwardly through the water up to a certain point, the greater the humidification, as it is this downward passage against the resistance of the water that causes the water 15 to be taken up by the air. The pipe 32 acts not only as an air inlet but when the water within the vessel 10 becomes exhausted or has been reduced to a point where it is no longer effective in humidifying the air, additional water may be sucked into the vessel 20 through the pipe 32 by the action of the engine as a suction means and by projecting the lower end of the tube 32 into a vessel containing water. 25

Having described my invention, what I claim is:

In a humidifier for an internal combustion engine; a vessel adapted to contain water, means for supporting said vessel, means detachably closing the top of said vessel, concentrically mounted tubular members arranged in said vessel and having closed upper and lower ends, said concentrically mounted vessels being alternately provided with openings adjacent the top and bottom thereof, a check valve controlled air inlet pipe passing centrally within the inner tubular member and terminating adjacent the bottom thereof, an air outlet leading from between the wall of the outer tubular member and the wall of the vessel, and a valve control pipe between the air outlet and the intake manifold of the engine.

In testimony whereof I affix my signature.

MILLARD FERN.
